(57) **CLAIM**

The ornamental design for an orthosis, as shown and described.

DESCRIPTION

FIG. 1 is a front perspective view of a first orthosis showing my new design;

FIG. 2 is a front view thereof;

FIG. 3 is a rear view thereof;

FIG. 4 is a right side view thereof;

FIG. 5 is a left side view thereof;

FIG. 6 is a front perspective view of a second orthosis showing my new design;

FIG. 7 is a front view thereof;

FIG. 8 is a rear view thereof;

FIG. 9 is a right side view thereof; and,

FIG. 10 is a left side view thereof.

The broken lines in the figures showing a human form are for the purpose of depicting environment and form no part of the claim. The broken lines in the figures showing

(Continued)

portions of the article form no part of the claim. The cross hatching utilized in the drawings indicates a contrasting appearance.

1 Claim, 10 Drawing Sheets
